EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUFT TUBE FOR TUBE FRAMES.

Application filed February 27, 1926. Serial No. 91,239.

This invention relates to tube frames for tuft weaving and particularly to the construction of the tuft tubes used in such frames to separate and guide the yarn-tufts for delivery to the fabric being woven.

Heretofore these tubes have been made of sheet metal blanks folded or bent longitudinally into the form of an elongated tube, somewhat flattened in cross-section, with the longitudinal edges of the metal blank in juxtaposition. As the dimensional requirements are such as to necessitate the use of thin metal in this construction it has been found, in practice, that such tubes have been subject to spreading or opening under the internal stress or pressure of the yarn tufts or of the threading needle which draws the appropriate yarn tufts through the individual tubes.

To remedy these defects, which have long been a source of complaint, I have provided a construction of tuft tube which, at the same time, presents no construction that is likely to catch against the warp threads between which the tuft tubes are inserted when supplying the tuft yarn to the fabric, and still provides an effective resistance to the objectionable opening of these tubes under internal pressure.

With these objects in view the invention comprises essentially a tuft tube formed out of an appropriate sheet metal blank and bent longitudinally into the form of an elongated tube of approximately ovoid cross section, the two longitudinal edges of the metal being so overlapped and interlocked or engaged with each other as to afford a positive resistance to spreading action exerted internally against the walls of the tube. This and other features of the invention will be explained in the following specification and will be defined in the claims hereto annexed.

In the accompanying drawings are illustrated several forms embodying the principles of this invention, in which:

Figure 1 is a front elevation of a tube frame carrying a row of tuft tubes, the middle portion being broken away.

Figure 2 is an enlarged detail view looking toward one end of a single tuft-tube to show the interlocking edges.

Figures 3 and 4 are detail views showing, respectively, a front view and an end edge

view of a blank for the manufacture of a modified form of tuft-tube.

Figures 5 and 6 are, respectively, rear elevations and side elevations of the tuft-tube formed from the blank shown in Figures 3 and 4.

Figure 7 is an end view of the same modified form of tuft-tube.

Figure 8 is an end view showing a modified construction for interlocking the overlapping edges of a tuft-tube.

The tube-frame to which the tuft-tubes are here shown applied is of a well-known type embracing a carrier-bar 1, spool-supporting and suspension brackets 2, and a yarn-spool 3.

To the front of the carrier-bar 1, is attached, in any suitable manner, a tube-holding member 5, of well known construction, embracing a longitudinal angle plate whose forwardly projecting member 5^a is slotted for the insertion of the individual tuft-tubes which are then soldered or otherwise secured to the angle plate 5.

The construction of the tuft-tubes 6, shown in Figure 1, is more clearly illustrated by the end view in Figure 2 from which it will be seen that a thin sheet metal blank of suitable form is bent or formed into an elongated somewhat flattened tube whose lower or free end is reduced or tapered to leave interstitial spaces for the reception of the individual warp threads in the loom. The reduced or lower end portions of all these tuft-tubes are approximately ovoid form in cross section, that is, instead of being elliptical or oval, usually the front, but sometimes the back, comes to more of a point than does the opposite narrow wall of the tuft tube. Preferably the joint between the two longitudinal edges is formed at the back where the back is wider than the front or if, as in some cases, the front is made wider than the back the joint is then made at the front.

In the simplest form the joint is formed, as shown in Figure 2, by lapping one longitudinal edge portion of the blank over or beyond the other, such longitudinal edge portions being of externally convex shape transversely to form a hook-like or interlocking engagement one with the other. These hook-like or interlocking edge por-

tions are shown at 6^a, 6^b, in Figure 2. This convex form of the overlapped edge portions of the tube need not extend to the enlarged inlet end of the tube at 6^c. This portion or head 6^c of the tube is preferably made flat to provide a flat bearing surface to rest against the face of the attaching strip or member 5, and does not require interlocking engagement as it is not so much subjected to spreading strains as it is of larger cross area than the lower ends of the tubes and as the heads mutually reenforce each other, besides being confined in the receiving slots of the attaching or backing strip. This form of interlocking engagement between the two overlapped edges of the tuft-tube is sufficient to resist all expanding or spreading strains to which the tube is subjected in ordinary usage.

20 Another form of interlocking joint tuft-tube is illustrated in Figures 3 to 7 inclusive. In this case the blank 7, of appropriate form, is provided near the edge portion that is to lie outside of the other edge portion with a slot or perforation 7^a, and directly across the blank near the opposite edge a small tongue 7^b is struck up from the body of the metal, said tongue being dimensioned to be inserted in the slot 7^a.

25 When the tube is formed from the blank the edge portion, containing the slot 7^a, is folded outside of the opposite edge portion, the tongue 7^b being inserted in the slot when the edges are overlapped in the described manner, and then being pressed down flat to form a reversely bent hook, as best shown in Figures 5 and 7.

30 Figure 8 shows an end view of a further modification in which the blank 8 has been formed along its longitudinal edges with two very narrow reversely folded hook portions 8^a and 8^b. For final forming opera-

40

tion these are pressed into engaging relationship so that, like the other forms described, the interlocking engagement resists the spreading strains of the yarn in service.

What I claim is:

1. A tuft tube for a tube-frame comprising a sheet metal blank of appropriate form bent longitudinally to form a partially flattened tube with the two longitudinal edges overlapped and interlockingly engaged to resist the opening of the tube under internal pressure.
2. A tuft tube formed of a single piece of sheet metal into an elongated tube open at both ends, a portion of one longitudinal edge of the metal being lapped beyond the other and forming a hook-like engagement therewith to resist spreading the tube under internal pressure.
3. A tuft tube for a tube-frame comprising a sheet metal blank bent longitudinally to form a tapered tube of approximately ovoid cross section, the longitudinal portions being lapped one over the other, the lapped portions being convexly curved in a transverse direction to form practically non-expansile engagement under internal stresses of service.
4. A tuft-tube for tube frames comprising a sheet metal blank formed into a flattened tube and having each of its longitudinal edge portions transversely bowed outwardly to form concavo-convex mutually over-lapping interlocking engagement with each other, thereby preventing the spreading apart of the side walls under the pressure of the interior tuft of yarn.

In witness whereof, I have subscribed the above specification.

EDGAR F. HATHAWAY.
